(No Model.)

W. H. BROWN.

MUSICAL PNEUMATIC TOY.

No. 398,697.

Patented Feb. 26, 1889.

UNITED STATES PATENT OFFICE.

WILLIAM HENRY BROWN, OF BOLTON, COUNTY OF LANCASTER, ENGLAND.

MUSICAL PNEUMATIC TOY.

SPECIFICATION forming part of Letters Patent No. 398,697, dated February 26, 1889.

Application filed November 15, 1888. Serial No. 290,923. (No model.) Patented in England September 5, 1888, No. 12,821.

To all whom it may concern:

Be it known that I, WILLIAM HENRY BROWN, cotton-spinner, of 64 Chorley Street, Bolton, in the county of Lancaster, England, have invented new and useful Improvements in a Musical Pneumatic Toy, (for which I have obtained a patent in Great Britain, No. 12,821, September 5, 1888,) of which the following is a specification.

10 This invention relates to that type of musical toys comprising reeds and disks mounted on cords, which, being twisted, as is well known, communicate revolving motions to the disks alternately in opposite directions by 15 alternately elongating and shortening the strings that are twisted together.

The object of my invention is to improve such toys and provide novel means for producing musical sounds; and to such ends the 20 invention consists in the features of construction and combination of devices hereinafter described and claimed, reference being made to the accompanying drawings, in which—

Figure 1 is a longitudinal elevation of my 25 musical pneumatic toy in operative position. Fig. 2 is a sectional elevation of the same through line O P in Figs. 3 and 4. Fig. 3 is a sectional view of the musical revolving toy through line S T in Fig. 2. Fig. 4 is an out- 30 side elevation of same, showing the openings or passages for conveying wind to the reeds. Fig. 5 is a front elevation of a disk with the reeds mounted thereon, and Fig. 6 is a plan view of one of the outer disks.

35 The musical portion A of this toy is composed of several parts, and consists of the plain disk B, as in Fig. 6, of card-board, to which is secured, by glue, gum, or other equivalent means, the center pieces, C. The circular 40 center pieces, C, are constructed, as in Fig. 3, with the circular openings D, to form passages between the outside disks, B and E, for conveying wind from the reeds when the toy is revolving. The card-board disk E is provided 45 with the openings or passages G for conveying wind to the reeds H, the latter being mounted on the circular metallic plate I, as in Fig. 5. The reed-plate I is attached to the card-board disk E in any convenient manner, 50 and around the periphery of the reed-plate is

arranged the ring J, that serves to support and rigidly connect the disk E to the center pieces, C, and at the same time hold the said disk E at such distances from the center pieces as to provide the required intervening space for the reed-plate. The reeds H are placed opposite the openings or passages G in the disk E, as shown in Figs. 2 and 3. Any convenient number of reeds can be mounted on the metallic plate I, the openings or passages D and G being provided to suit. The whole of the parts forming the musical toy are put together as in Figs. 1 and 2, and are secured by means of glue, gum, or other equivalents.

If desired, the several parts of the toy, with the exception of the plate I and reeds H, which are in all cases of metal, may be made of metal, wood, papier-maché, or other suitable materials.

The metallic plate I is provided with the holes K, through which the double cord L passes, the latter having the handles M at each end for operating the toy in the following manner: The operator places one of the 75 handles M in each hand and revolves the toy until the double strings or cords L are twisted sufficiently to contract the length of the same, as in Fig. 1. Then by distending the hands the tendency is to untwist the cords L, which 80 at once sets the toy revolving, the speed being according to the speed or movement of the operator's hands. By allowing the hands to move to and fro the toy A is revolved first in one direction and then in the other without any perceptible stoppage, and so on as long as desired. By the revolving action of the toy the reeds H are operated by atmospheric air passing through the openings or 85 passages G and out by the openings D on the periphery of the same, as indicated by the arrows. The musical sounds from the reeds H can be varied in tone, according to the speed at which the disk A is revolved. The outside of the disks B and E can be ornamented in colors or with colored scraps, to make the same 90 attractive and pleasing to the eye.

I claim as my invention—

A musical revolving toy consisting of the cords L, the plain disk B, having the circular 100

center pieces, C, fixed thereto and provided with the circular chambers or openings D, extending to their periphery, the ring J, secured to the periphery of the center pieces, 5 the outer disk, E, having radial air-passages G and secured on said ring, and the circular reed-carrying plate I, fitted inside said peripheral ring between the center pieces and the outer disk having the air-openings, substantially as described.

In testimony whereof I affix my signature in presence of two witnesses.

WILLIAM HENRY BROWN.
